UNITED STATES PATENT OFFICE.

WILLIAM T. SMITH, OF PHILADELPHIA, PENNSYLVANIA.

DESIGN FOR WOVEN FABRIC.

SPECIFICATION forming part of Design No. 34,738, dated July 2, 1901.

Application filed June 6, 1901. Serial No. 63,474. Term of patent 7 years.

To all whom it may concern:

Be it known that I, WILLIAM T. SMITH, a citizen of the United States, residing in Philadelphia, Pennsylvania, have invented and produced a certain new and original Design for a Woven Fabric, of which the following is a specification.

My design is shown in the accompanying drawing, which represents sufficient of the pattern to illustrate the design, the remainder being simply a repetition of what is shown.

The design is of a geometrical character, and comprises the two figures 1, a series of figures 2, and a number of blocks 3. The figures 1 each have zigzag outlines and comprise a border consisting of dark and light zigzag bands

4 and 5 and a central ornament 6. The figures 2 and blocks 3 are composed of alternating light and dark triangular members.

Having thus described my invention, I claim and desire to secure by Letters Patent—

The design for a woven fabric, substantially as described and as shown in the accompanying drawing.

In testimony whereof I have signed my name to this specification in the presence of two subscribing witnesses.

WILLIAM T. SMITH.

Witnesses:
